[57] CLAIM

The ornamental design for a muscle stimulating pulse generator, as shown.

DESCRIPTION

FIG. 1 is an isometric view of the muscle stimulating pulse generator embodying our design;

FIG. 2 is a front elevational view of the muscle stimulating pulse generator of FIG. 1;

FIG. 3 is a side elevational view of the muscle stimulating pulse generator of FIG. 1;

FIG. 4 is a rear elevational view of the muscle stimulating pulse generator of FIG. 1; and

FIG. 5 is a bottom plan view of the muscle stimulating pulse generator of FIG. 1.
